(57) **CLAIM**

The ornamental design for a flat panel computer having an integrally housed flat panel display, as shown and described.

DESCRIPTION

FIG. 1 is a perspective view of the design for the flat panel computer having an integrally housed flat panel display, wherein the flat panel computer includes a disc drive shown in solid lines, wherein the flat panel computer includes a floppy disk drive, a volume dial, a display adjustment dial, a power button, and a reset button shown in dashed lines; FIG. 2 is a front elevational view of the design for the flat panel computer having an integrally housed flat panel display as illustrated in FIG. 1; and,

FIG. 3 is a left side elevational view of the design for the flat panel computer having an integrally housed flat panel display as illustrated in FIG. 1.

In these drawings, the solid lines illustrate the claimed ornamental design, whereas the broken lines illustrate environmental features that form no part of the claimed ornamental design of the subject embodiment.
